CLAIM

The ornamental design for a mobile phone, as shown and described.

DESCRIPTION

1. Mobile phone
- 1.1 : Perspective
- 1.2 : Front
- 1.3 : Back
- 1.4 : Left
- 1.5 : Right
- 1.6 : Top
- 1.7 : Bottom

The broken lines immediately adjacent to the claim, encompassing unshaded regions, represent the bounds of the claimed design while all other broken lines are directed to environment and are for illustrative purposes only; the

(Continued)

broken lines form no part of the claimed design. In addition, the unshaded surface in Figures 1.1, 1.2 and 1.4-1.7 that directly adjoins the claimed solid line edge forms no part of the claimed design.

1 Claim, 6 Drawing Sheets
